UNITED STATES PATENT OFFICE.

LEONARD H. WHEELER, OF CHICAGO, ILLINOIS, ASSIGNOR TO STEWART-WARNER SPEEDOMETER CORPORATION, OF CHICAGO, ILLINOIS, A CORPORATION OF VIRGINIA.

VACUUM FEED DEVICE.

Application filed September 13, 1922. Serial No. 587,908.

To all whom it may concern:

Be it known that I, LEONARD H. WHEELER, a citizen of the United States, residing in the city of Chicago, in the county of Cook and 5 the State of Illinois, have invented certain new and useful Improvements in Vacuum Feed Devices, of which the following is a specification, reference being had to the accompanying drawings, forming a part there- 10 of.

The purpose of this invention is to provide a vacuum fuel feeding device whose interior operation can at all times be observed by the driver of the car whose engine it 15 serves, and which shall be of the simplest possible construction in respect to the means for lifting the fuel and delivering it to the carburetor. It consists in the elements and features of construction shown and described 20 as indicated in the claims.

In the drawings:—

Figure 1 is a diagrammatic view showing an engine equipped with a fuel feeding device embodying this invention.

25 Figure 2 is a top plan view of the vacuum chamber of the fuel feeding device having its shell partly broken away and shown in transaxial section at the break.

Figure 3 is a section at the line 3—3 on 30 Figure 2.

The structure shown in the drawings comprises the engine, 1, having carburetor, 2, in the usual position, a low level main fuel supply tank, 3, a suction pump, 4, mounted upon the engine and driven thereby by any suitable connection, indicated by shaft, 4^a, leading out of the engine base; a suction pipe, 5, leading from the pump, 4, to the suction connection of the vacuum chamber, A, a fuel 35 supply connection, 7, leading from the main supply tank, 3, to the vacuum chamber and a fuel delivery connection, 8, leading from the vacuum chamber to the carburetor. 40

The vacuum chamber comprises a trans- 45 parent body, 9, and metal bottom plate, 11, metal top plate, 12, having a skeleton cylinder extension comprising narrow longitudinal bars, 12^a, terminating at the lower end in an annulus, 12^b, which is exteriorly 50 threaded for receiving screwed onto it the bottom plate, 11, which for that purpose has a marginal upturned flange, 11^a. The trans- 55 parent body, 9, is clamped firmly between the top and bottom plates in the screwing

on of the bottom plate to the annulus, 12^b, 55 suitable packing gaskets, 10, being interposed at both ends of said transparent body. The top plate, 12, has fuel supply inlet at 21, at which the pipe, 7, leading from the low tank is coupled. It has also suction port at 17, 60 at which the suction pipe, 5, is connected. It has also the atmosphere inlet, 20. A valve 16, controls the suction connection, 17 and a valve, 19, controls the atmosphere inlet, 20. The valve, 16, is mounted on a stem, 13, which 65 extends vertically through the center of the chamber and is guided at its lower end in a fitting, 11^c, screwed into the outlet orifice, 11^d, of the bottom plate, 11. The valve, 19, is carried rigidly with the stem, 13, by means 70 of an arm, 18, extending transversely from said stem, 13, and carrying rigidly the valve, 19, whose stem is attached to said arm, 18. The two valves, 16 and 19, thus move together for seating the one when the other is 75 opened. A float, 26, mounted for sliding on the stem, 13, between a stop, 14, near the lower end and a stop, 15, a short distance below said arm, 18, operates the valves for closing the suction communication and opening the atmosphere communication at a pre- 80 determined high level of liquid in the chamber, and reversely operating said valves at a predetermined low level when the float, 26, has receded to the stop, 14. A deflector, 22, 85 on the under side of the top plate under the fuel inlet port, 21, serves to deflect the stream of fluid toward the wall of the chamber preventing it from impinging upon the float and thereby interfering with its normal action. The discharge connection from the vacuum chamber to the carburetor is made by means of a "reducer" pipe fitting, 24, screwed onto the exteriorly threaded boss, 11^e, through which the discharge ori- 90 fice is formed; said reducer fitting being of such length as to afford a valve chamber below the end of the boss in which the check valve, 23, is located, the end of the boss being suitably finished to afford a seat for the 100 valve which seats upwardly under the influence of the suction in the chamber, and is adapted to be opened by the gravity flow of liquid from the chamber upon the interruption of the suction and recurrence of at- 105 mosphere pressure in the chamber.

It will be seen that the construction described constitutes a fuel feeding device

operated by suction for lifting the fuel from the low level source and delivering by gravity to the carburetor in which there is required only a single chamber constituting both vacuum chamber and reservoir, which in view of the fact that adequate suction will always be afforded by the positively operating pump to fill the vacuum chamber almost instantly, makes it possible to employ a relatively small vacuum chamber so that the interruption of gravity flow to the carburetor during the time of filling the vacuum chamber will be negligible. And the operation of the vacuum chamber being at 20 times observable through the transparent body, 9, the driver will be able to note instantly any cessation of operation whether due to functional derangement or to exhaustion of supply in the main tank.

20 I claim:

1. A vacuum fuel feeding device comprising a chamber having atmosphere inlet, fuel supply and delivery connections, and float-controlled means for alternating the dominance of atmospheric pressure and suction above the liquid in said chamber, the bottom plate of said chamber having a central exteriorly threaded boss through which the discharge orifice is formed, a pipe reducer fitting screwed onto said boss constituting a valve chamber therebelow, the end of the boss being adapted to serve as a valve seat, and an upwardly seating check valve in said chamber, the carburetor supply connecting pipe leading from the lower reduced terminal of said reducer.
2. A vacuum fuel feed device comprising a transparent body with metal top and bottom plates; fuel inlet and outlet connections and atmosphere inlet and suction connections being made through said metal plates; float-operated valves controlling certain of said connections, said controlling float being exteriorly visible through the transparent body, the top and bottom plates being connected by a skeleton cylinder formed integrally with one of said members and adapted for attachment to the other, the transparent body being encompassed by said skeleton cylinder and clamped endwise between the top and bottom plates by the joining of said metal members.

3. A vacuum fuel feed device comprising a transparent body with metal top and bottom plates; fuel inlet and outlet connections and atmosphere inlet and suction connections being made through said metal plates; float-operated valves controlling certain of said connections, said controlling float being exteriorly visible through the transparent body, the top and bottom plates being rigidly connected by a skeleton cylinder consisting of longitudinal bars extending rigidly from one of said plates and terminating in an annulus exteriorly threaded for screw connection with the other plate, the transparent body being clamped endwise between the two plates by said screw connection.

In testimony whereof I have hereunto set my hand at Chicago, Illinois, this 5th day of September, 1922.

LEONARD H. WHEELER.
